UNITED STATES PATENT OFFICE.

MARY E. TOWLER, OF HUBBARD, TEXAS.

PIN-FASTENER.

1,155,691

Specification of Letters Patent.

Patented Oct. 5, 1915

Application filed October 1, 1914. Serial No. 864,443.

To all whom it may concern:

Be it known that I, MARY E. TOWLER, citizen of the United States, residing at Hubbard, in the county of Hill and State 5 of Texas, have invented certain new and useful Improvements in Pin-Fasteners, of which the following is a specification.

This invention relates to devices for fastening in place jewelry pins, buttons, and 10 other similar articles, and has as one of its objects to provide means whereby such articles may be securely fastened in place, as against accidental or surreptitious removal, the means whereby the articles are 15 to be so held being, however, so constructed as to permit of their ready removal whenever desired.

The invention also aims to provide a pin fastening device for the purpose stated, so 20 constructed that the insertion of the pin in an article of wearing apparel will not be likely to mutilate or tear the apparel at the point of insertion.

The invention also has as its object to 25 provide a novel means for securing the pin fastening device at its head end into the head of the pin or into the button or other article to be supported thereby.

In the accompanying drawings: Figure 1 30 is a perspective view of one form of the invention, illustrating the manner in which the same is adapted to be applied to a garment. Fig. 2 is a side elevation of the device, shown in Fig. 1, applied, the ply 35 through which the pin is inserted being shown in section. Fig. 3 is a group perspective view, illustrating the pin and the head thereof separated. Fig. 4 is a view similar to Fig. 3, illustrating the form of 40 pin fastening device employed for attaching buttons to a garment, the button being separated from the pin.

Corresponding and like parts are referred to in the following description and indicated in all the views of the accompanying drawings by the same reference characters.

In the drawings, the shank of the pin fastening device is illustrated by the numeral 1 and at one end is pointed, as at 2, in the 50 usual manner, to permit of its ready insertion through one or more plies of cloth, and adjacent its upper end, the wire from which the shank 1 is formed is bent slightly laterally, as at 3, and thence upon itself, as at 4, 55 to form a portion 5 which is spaced from the portion 3 and non-parallel thereto, as will

be apparent by reference to Figs. 3 and 4 of the drawings. More specifically stated, the portion 5, as formed by the bend 4, lies substantially parallel to the main portion 6 of the shank of the pin and consequently, the portions 3 and 5 converge toward their lower ends. Beyond the lower end of the portion 5, the wire from which the pin is formed is bent to extend at right angles to 65 the plane occupied by the portions 3 and 5, as indicated at 6, and thence several times upon itself, as at 7, to form a head consisting of a number of initially spaced strands, which, due to the resiliency of the wire from 70 which the pin is formed, have a tendency to separate, so that the head, as a whole, prior to its connection with the head of the pin or button, is expanded.

In that form of the invention shown in 75 Figs. 1 to 3 inclusive, the numeral 8 indicates the head proper of the pin, which head may be of the form shown or of any other desired form, and suitable for use as a scarf pin or as a pin intended merely for 80 use in fastening or closing a garment, and this head is formed axially with an opening 9 which is of a diameter slightly less than the diameter of the head 7 in its expanded condition. In assembling the parts, the 85 head 7 is contracted and fitted into the opening 9 and permitted to expand against the wall of the said opening, and in this manner the parts are securely and permanently connected. As before stated, a button may take 90 the place of the head 8, and such a button is shown in Fig. 4 of the drawing and indicated by the numeral 10.

It will be apparent by reference to Figs. 1 and 2, that in either embodiment of the 95 invention, the pin will be securely locked in place and held against accidental or surreptitious removal when its shank 1 has been inserted through the garment and the parts 3, 4 and 5 have been brought to position at the inner side of the garment. It will also be apparent that the pin may be readily removed when desired by so positioning the plies of the garment that downward movement of the pin will cause its portion 5 to ride through the opening made in the garment by the shank of the pin, after which a slight lateral movement of the pin will permit of its outward withdrawal without further interference. 105

It will be observed that the lower end of the portion 5 of the pin shank is located

close to the bend connecting portion 3 with the main portion of the shank so that the head of the pin will have its axis located in a line intersecting the line of the shank 5 and there will be no likelihood of the head turning to one side. It will also be understood that by reason of this construction, the open loop formed by the bend 4 has a contracted front which provides against the 10 pin being surreptitiously removed by a quick forward movement followed by a quick upward movement.

Having thus described the invention, what is claimed as new is:

15. 1. A fastening of the class described formed adjacent one extremity to provide a loop having its sides disposed in a common plane and provided with a head supporting portion extending laterally from the plane 20 of said sides at substantially right angles thereto, and a head adjustable upon the head supporting portion toward the sides of said loop.
2. A fastening of the class described having a portion of its length formed into a 25 yieldably expansible head supporting por-

tion, and a head carried by the head supporting portion and yieldably engaged thereby.

3. In a fastening device of the class described, a pin shank provided at its upper end with a head supporting portion, the said shank being bent upon itself a number of times to form the said portion and the said portion being initially expanded, 30 and a head having an opening detachably receiving said portion in contracted condition.

4. A fastening of the class described including a pin shank rebent upon itself at 40 one extremity a number of times to provide a plurality of overlapping portions normally expanded to form a head receiving portion, and a head having an opening detachably receiving said portion in contracted condition.

In testimony whereof I affix my signature in presence of two witnesses.

MARY E. TOWLER. [L.S.]
